UNITED STATES PATENT OFFICE.

ERNEST SCHATTNER, OF EALING, ENGLAND.

ELECTRIC FUSIBLE CUT-OUT.

948,296.

Specification of Letters Patent.

Patented Feb. 1, 1910.

Application filed June 11, 1907. Serial No. 378,428.

To all whom it may concern:

Be it known that I, ERNEST SCHATTNER, a subject of the King of Great Britain and Ireland, residing at 48 Culmington road, 5 Ealing, county of Middlesex, England, have invented new and useful Improvements in Electric Fusible Cut-Outs, of which the following is a specification.

My invention relates more particularly to 10 electric fuses of the inclosed or cartridge type in which granular or powdered material such as sand is used for extinguishing the arc which tends to form between the terminals when the fuse is ruptured. Fuses of 15 this kind when filled with a material like sand which is excellent for extinguishing the arc, have been found to be altogether unreliable when used on circuits of large capacity owing to the fact that the sand filling 20 becomes conductive at high temperatures and reestablishes the circuit a short time after the fuse has blown.

The primary object of my invention is to overcome this difficulty and to this end it 25 consists in combining with the fuse means containing a cooling liquid or gas which is liberated by rupture of the fuse so as to cool down the granular filling and the arc which tends to form at the instant of rupture and 30 thereby insure certainty of safe operation.

My invention is illustrated in the accompanying drawing which represents a fuse partially broken away.

Referring to the drawings, 1 indicates the 35 fuse or cut-out as a whole, having caps 2, 3 provided with suitable lugs 4, 5. The cartridge chamber is comprised within the cylindrical tube of fiber or other suitable material 6 and accommodates the fuse wire 7 in 40 the usual way. The cartridge chamber is filled with granular material 8 such as sand or the like and above the fuse wire is located one or more cylinders or otherwise suitably shaped fragile or easily fusible containers 9 45 filled with a cooling fluid such as water or it may be gas under high pressure. If desired the containers may be filled with a liquid or gas which when liberated so as to come into contact with a suitable substance mixed with 50 the sand or other filling material for the cartridge, will chemically re-act with said substance and suddenly liberate a large volume of gas helping to cool and extinguish the arc.

For example, the sand or other filling for the cartridge may be mixed with bi-carbonate of 55 soda and the fragile container filled with a solution of tartaric acid in water, so that when the container is broken the tartaric acid will combine with the soda, liberating a large volume of carbonic acid gas which acting in conjunction with the liquid will serve to cool down and extinguish the arc which tends to be maintained between the fuse terminals upon rupture of the fuse. 60

It will be understood that the fragile vessel 65 will be broken or melted to liberate the cooling fluid by the heat or the pressure of the vaporized fusible conductor at the instant the conductor melts or vaporizes.

What I claim as new and desire to secure 70 by Letters Patent of the United States is:—

1. A fusible cut-out comprising in combination a chamber, a fuse and a filling material therein, and means adapted to liberate a cooling fluid on the rupture of the fuse. 75

2. A fusible cut-out comprising in combination a chamber, a fuse therein, filling material within said chamber and means for liberating a cooling fluid to extinguish the arc. 80

3. A fusible cut-out comprising in combination a chamber, a fuse therein, filling material within said chamber and a frangible vessel containing a cooling fluid adapted to be liberated by the rupture of the fuse. 85

4. A fusible cut-out comprising in combination a chamber, and a fuse therein, a frangible vessel containing a cooling fluid located adjacent the fuse-wire and filling material within the chamber surrounding said fuse-wire and frangible vessel. 90

5. A fusible cut-out comprising in combination a chamber, a fuse therein, a frangible vessel containing a fluid adapted to be liberated by the rupture of the fuse, filling material within the chamber surrounding said fuse and frangible vessel and a substance mixed with the filling material capable of chemical reaction with the fluid liberated by the rupture of the fuse. 95

In witness whereof I have hereunto set my hand this 29th day of May, 1907.

ERNEST SCHATTNER.
